UNITED STATES PATENT OFFICE.

WILLIAM F. SCHANZLIN, OF LIMA, OHIO.

STEAM-BOILER.

1,360,030.

Specification of Letters Patent. Patented Nov. 23, 1920.

Application filed June 18, 1919. Serial No. 304,992.

To all whom it may concern:

Be it known that I, WILLIAM F. SCHANZLIN, a citizen of the United States, and a resident of Lima, in the county of Allen and 5 State of Ohio, have invented a new and Improved Steam-Boiler, of which the following is a full, clear, and exact description.

The present invention relates to new and useful improvements in steam boilers, and 10 pertains more particularly to that class of boilers commonly known as the water-tube type.

The primary object of the present invention is to construct a water-tube boiler in 15 such a manner that the water tubes are subjected to the greatest possible amount of heat generated by the furnace.

A further object of the invention is to construct a water-tube boiler in such a manner that the cross-over tubes generally employed in devices of this character are entirely eliminated, thus doing away with dead air space, and the consequent loss of heat.

A still further object of the invention is 25 to provide a plurality of upper drums and means for securing the drums together.

With the above and other objects in view, reference is had to the accompanying drawings, in which—

30 Figure 1 is a vertical sectional view of a steam boiler furnace, the water tubes and drums being shown in end elevation;

Fig. 2 is a detail sectional view of a portion of one of the upper drums;

35 Fig. 3 is a detail sectional view taken on the line 3—3 of Fig. 2;

Fig. 4 is a detail perspective sectional view of the means employed for securing the upper drums together.

40 Referring more particularly to the drawings, the reference character 5 designates the furnace housing, and 6 represents the grate bars thereof. The reference character 7 designates the bridge wall, and mounted

45 to the rear of said bridge wall 7, is a large lower water drum 8, which extends across the furnace housing 5. This drum 8 is provided with an inlet pipe 9, by means of which the water is supplied thereto, said drum being further provided with a clean-out opening 10, as shown in Fig. 1.

Mounted in the upper end of the furnace housing 5, are two drums 12, and connecting each of said drums 12 with its respective side of the longitudinal axis of the drum 8, are water tubes 13. These water tubes are

connected to the upper drums 12 in any desired manner, and are arranged as shown in Fig. 1, in two sets, one set being secured to the one side of the longitudinal axis of the 60 drum 8, the other set being secured to the opposite side of the longitudinal axis of said drum.

Referring to Figs. 3 and 4, the means by which the two upper drums 12 are secured together will be seen to comprise a metallic body portion 15, upon the opposite edges 16 of which are formed oppositely disposed flanges 17, which are provided with a plurality of spaced openings 18, the purpose 65 of which will be hereinafter described. The body portion 15 is provided with a plurality of elongated openings 19, which pass entirely therethrough, and the drums 12 on their opposed faces are likewise provided 70 with openings 20 adapted to register with the openings 19 in the body portion 15 heretofore mentioned. The flanges 17 are so shaped that they conform to the general contour of the drums 12, and as shown in Fig. 75 80 3, the securing means is placed between the drums 12, with the flanges 17 in contact with the outer surface of each of the drums.

The body portion 15 is then secured in place by means of rivets or the like 21, 85 which pass through openings in the drums 12 at points where they will register with the openings 18 and the flanges 17. By this construction, it is apparent that the two drums 12 may be secured together in rigid 90 relation to each other, and, at the same time, communication between the drums is established through the elongated openings 19. Leading from each of the drums 12, is a discharge pipe 22, the ends of said discharge 95 pipe 22 being connected by means of a T-coupling 23, which in turn is connected to the main discharge pipe 23, by means of which the steam as generated is carried off.

By this construction, it will be seen that 100 the lower drum 8 is at all times in communication with the upper drums 12, through the medium of the circulating water tubes 13, and that the drums 12 are in communication with each other as hereinbefore stated, 105 thus permitting of a complete circulation of the water taking place under the influence of the heat of the furnace.

I claim:

1. A water tube boiler comprising a lower 110 drum, a plurality of upper drums arranged in spaced relation to each other, a plurality

of water tubes connecting the lower drum with the upper drums, and means for securing the upper drums together and establishing communication therebetween, said securing means comprising a bar, the body of which is provided with a plurality of spaced perforations, each of the side edges of said bar being formed with two outwardly flared spaced flanges perforated to provide for 10 their attachment to their respective drums.

2. In combination with a plurality of

water containers adapted to be secured together in communication with each other, a bar, the body portion of which is provided with perforations in spaced relation to each other, said bar being formed on its side edges with outwardly flared flanges perforated to receive the securing means by which the containers and the bar are secured together to provide a unitary structure. 20

WILLIAM F. SCHANZLIN.
